BOWLING BALL BUMPER AND TABLE SUPPORT FOR AUTOMATIC PIN POSITIONING MACHINES

Joseph C. Clark, Merchantville, N. J., assignor to American Machine and Foundry Company, a corporation of New Jersey.

Application December 31, 1947, Serial No. 795,075

14 Claims. (Cl. 273—43)

1

This invention relates to automatic bowling pin setting machines and more particularly apparatus for counterbalancing heavy moving parts of a bowling pin setting machine.

Most bowling alleys in existence today were not constructed to support heavy automatic pin setting machines. When a series of bowling pin setting machines are mounted side by side in a bowling alley, the floor load capacities must not be exceeded and it will be appreciated that most bowling alleys will have very definite limitations in this respect. It has therefore been a problem to design an automatic pin setting machine, which will not only be reliable in operation but which will also be practicable in that it will be light enough to be used in a large number of alleys not originally designed to support automatic pin setting machines.

It is therefore an object to provide apparatus whereby the bumper hanging across the pit of a bowling alley will be interconnected with a respotter table so that one will counterbalance the other to eliminate the need of separate counterbalancing devices and thus enable less power to be used to raise and lower the respotter table.

A further object is to interconnect and synchronize the movements of a bowling pin spotting and respotting table and a bumper hanging across the pit of a bowling alley to place one in operative position while the other is removed from operative position.

Another object is to reduce the amount of weight of a bowling pin setting machine by counterbalancing two operating members with each other.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

Fig. 1 is a side elevation partly in cross section showing my apparatus for counterbalancing the bowling pin setting and resetting table and the bowling ball bumper.

Fig. 2 is a front elevation taken on line 2—2 of Fig. 1.

My invention is particularly well suited for use with an automatic bowling pin setting machine employing a table which travels towards and away from a bowling alley to set and reset bowling pins on the bowling alley and a cushion hang-

2

ing across the pit of the bowling alley for stopping thrown bowling balls. If desired reference may be made to U. S. Patent 2,346,189 issued to G. J. Schmidt on April 11, 1944, for an automatic pin setting machine comprising a traveling table and a cushion of the type to which I refer.

The respotter table 10 is mounted for vertical movement above a bowling alley 12 on which bowling pins are spotted. Guide channels 14 are mounted on either side of the respotter table 10 and are secured to the kickback walls 18 and 20 at the back end of the bowling alley. Various types of tables may be employed for setting and resetting bowling pins on a bowling alley of which the type shown is purely illustrative.

For purposes of illustration and without intent to limit the scope of this invention, I have shown a table employing cone shaped pin resetting grippers 22 and spotting grippers 24 for positioning pins on the bowling alley. For a more detailed description of how the pin setting and resetting grippers operate reference may be made to the above patent and to patent No. 2,217,709 issued to G. J. Schmidt on October 15, 1940.

The spotting and respotting table 10 is supported on opposite sides by studs 25 pivotally mounted in the sliding guide shoes 26 which slide up and down in guide channels 14. Sliding guide shoes 26 are connected to and supported by one end of cables 28, the other ends of cables 28 being fixedly connected to pulleys 30 mounted on either side of the bowling alley. Pulleys 30 are fixedly mounted on the shaft 32 on which is also fixedly mounted a pinion 34. Rack 36 is held in engagement with the pinion 34 by means of a guide roller 38.

Cables 42 are connected at one end to a pair of pulleys 40 fixedly mounted at opposite ends of shaft 32 and travel over a pair of pulleys 44 and 46 mounted at opposite ends of the shaft 92. The other ends of cables 42 are connected to sliding guide shoes 48 and 50 which travel up and down in guide channels 52 and 54. A bracket 56 connected at its ends to the guide shoes 48 and 50 by suitable means such as bolts 58 and 60 serves to maintain the shoes 48 and 50 in their respective channels 52 and 54. A pair of hooks 62 and 64 formed on the lower side of bracket 56 support a conventional hanging cushion 66 by engaging with the eye bolts 68 and 70 attached to the upper side of the cushion 66. The guide channels 52 and 54 are fixedly mounted on the upper sides of the kickback walls 18 and 20 as shown in Fig. 2.

Mounted across the floor of the pit of the

bowling alley is a suitable device such as the continuously traveling belt 72 which travels over rollers 74 and 76 in the direction indicated by the arrow to forward pins and bowling balls towards the rear end of the pit where suitable means are employed for elevating and removing the bowling ball and bowling pins from the pit of the bowling alley. If desired reference may be made to copending application of R. E. Rundell, S. N. 706,472, filed October 29, 1946, for apparatus suitable for this purpose which could be used for removing a bowling ball and bowling pins from the pit of the bowling alley.

Rack 36, mounted on one end of the connecting rod 78 receives reciprocatory motion from the arcuate movements of arm 80. Arm 80 is fixedly mounted on shaft 84 which is freely supported at each end in suitable bearings attached to brackets 82 mounted on the frame 86 of the automatic pin setting machine.

A suitable coiled tension spring 85 is mounted on the shaft 84 and is fixed at one end to the collar 87 and at the other end to bracket 82 so that there will be sufficient tension exerted on the arm 80 to hold the cam follower 88 in engagement with cam 90 at all times. Cam 90 is fixedly mounted on shaft 92 which is rotatably supported at each end in bearing brackets 94 and 96. Bearing brackets 94 and 96 are fixedly connected to brackets 82.

Driving gear 98 is fixedly mounted on the shaft 92 and receives driving movement from a pinion 100 which is fixedly mounted on a shaft 102. Shaft 102 is freely supported in suitable bearing brackets 104 and 106. Also fixedly mounted on shaft 102 is a sprocket 108 intermittently driven by sprocket chain 110 from the main shaft, not shown, of the automatic pin setting machine.

The operation of my invention may be briefly described as follows:

After a player has thrown a bowling ball it will strike against the bumper 66 which absorbs the momentum of the bowling ball which then falls into the pit of the bowling alley. The bowling ball in rolling along the alley into the pit actuates a suitable detector such as a photo-electric cell or switch such as shown in the aforementioned application of R. E. Rundell, S. N. 706,472 which indicate that a bowling ball has been thrown and sets the automatic pin setting machine in operation.

At the proper time in the cycle of operation of the automatic pin setting machine, the table 10 is lowered toward the bowling alley into contact with any pins which remain standing on the alley. Suitable detectors associated with the cone shaped pin resetting grippers 22 indicate which pins, if any, remain standing after the bowling ball has been thrown. As the table 10 descends the bumper 66 will be elevated thereby allowing the thrown ball to pass to the rear of the alley. If the ball thrown constitutes the first ball in a frame, the gripping devices 22 on the respotter table 10 grip and elevate the standing pins above the alley and a suitable sweeping device such as shown in U. S. patent issued to R. E. Rundell 2,250,503, dated July 29, 1941, pushes the fallen pins to the rear of the alley into the pit. The respotter table 10 is then lowered to replace the gripped pins on the alley to enable the player to throw his second ball in the frame.

In the event of a strike on the first ball in a frame, the table 10 would be elevated without any pins since they were all knocked down. The machine would then go through a strike cycle

clearing the alley of all fallen pins. Table 10 is then rotated 180° before being lowered to place a new set of pins carried by the pin gripping cups 24 on the alley. Each time the table 10 is lowered, the bumper 66 is raised thereby allowing the bowling ball and pins to travel freely under the bumper 66 towards the rear of the pit into the range of action of suitable ball and pin elevating mechanism. It will be noted that the operating cycles of the table 10 and bumper 66 alternate and when one device is lowered into operating position the other is simultaneously raised out of operative position.

If the thrown ball constitutes the second ball in a frame, the spotting and respotting table 10, after having been lowered to indicate which pins remain standing on the alley, is raised without elevating any of the standing pins. A suitable sweep such as referred to above is then actuated to push both standing and fallen pins from the alley into the pit. The respotter table is then rotated 180° on its pivotally supported studs 25 so as to bring the gripping cups 24, containing a new set of bowling pins, above the alley 12. The table 10 is then lowered by the actuation of chain 110, to set a new set of pins in playing arrangement on the alley. It will be understood that while I have referred to and illustrated a table which rotates about its axis 180°, non-rotating spotting and respotting tables which travel towards and away from the bed of a bowling alley could be used equally as well for this purpose and my invention is not intended to be restricted for use with the specific type of table used to illustrate the invention. If desired reference may be made to copending application of W. C. Broekhuysen, S. N. 627,605, filed November 9, 1945, which matured as Patent No. 2,559,274, July 3, 1951, for apparatus suitable for controlling the operation of an automatic pin setting machine.

The table 10 is raised and lowered in the manner described by means of the cables 28 which raise and lower guide shoes 26 in the channels 14. The guide shoes 26 to which the table 10 is pivotally connected and the guide shoes 48 and 50 to which the bumper 66 is connected by means of the supporting bracket 56 are lowered and raised by means of cables 28 mechanically associated with cables 42. The cables 28 and 42, which are fixedly connected to their respective pulleys 30 and 40 are wound up and unwound from these pulleys by the reciprocation of the rack 36 which engages with the pinion 34. Since the pulleys 30 and 40 are of different diameters, the distances traveled by the table 10 and bumper 66 will vary accordingly and this also allows for a corresponding difference in weight between the table 10 and the bumper 66.

The reciprocation of the rack 36 which is mounted on the end of connecting rod 78 is controlled by the contour of cam 90 against which the cam follower 88 is held by means of the coiled tension spring 85. The cam 90 is rotated through a complete cycle by its driving mechanism consisting of the sprocket chain 110, sprocket 108, shaft 102, pinion 100, drive gear 98 and shaft 92. Sprocket chain 110 is connected to a suitable source of power and is driven for a predetermined length of time, each time the bowling ball is thrown, to move the cam 90 through a complete cycle of rotation.

When the table 10 is lowered the bumper 66 is raised due to the fact that pulleys 40 and 30 are mounted on the same shaft 32 and therefore each device counterbalances the other. I have there-

fore provided a simple device which synchronizes the raising and lowering of the bumper 66 with the lowering and raising of the pin setting and resetting table 10, both of which constitute two rather heavy parts of an automatic pin setting machine. The device I have shown for using the weight of the bumper to counterbalance the weight of the spotting and respotting table is economical to construct and also lessens the weight of the machine in that a special counterweight is not required to be used to counterbalance the table.

The ball and pins which are discharged into the pit of the bowling alley are forwarded to the rear of the alley due to the traveling movement of belt 72. Suitable mechanism such as that shown in copending application of Rupert E. Rundell, S. N. 706,472, referred to hereinbefore may be used for removing the bowling ball and bowling pins from the pit of the bowling alley. While the bumper or cushion 66 in the apparatus used to illustrate the invention is spaced from the traveling belt 72 a distance greater than the diameter of a bowling pin to thereby allow pins to pass thereunder at all times to a pin elevator at the rear of the pit, other pin removing arrangements could be employed equally as well with this invention. To make sure the bumper stops the thrown bowling ball it is preferable to have the bumper spaced from the traveling belt 72 a distance less than the diameter of a bowling ball as shown in Figures 1 and 2.

The invention above described may be varied in construction within the scope of the claims, for the particular device selected to illustrate the invention is but one of many possible embodiments of the same. The invention, therefore, is not to be restricted to the precise details of the structure shown and described.

What is claimed is:

1. In an automatic bowling pin setting and resetting machine having a bumper for stopping bowling balls and a table for placing a new set of pins on the alley and lifting standing pins above the alley, a support for said table adapted and arranged to suspend said table for vertical movement, a support for said bumper adapted and arranged to suspend said bumper for vertical movement, and mechanism interconnecting said table support and said bumper support to counterbalance the weights of said bumper and said table against each other.

2. In an automatic bowling pin setting and resetting machine having a bowling ball bumper, and a spotting and respotting table, mechanism interconnecting said bumper and table comprising vertically movable guide supports connected to opposite sides of said table, vertically movable guide supports to which said bumper is attached, an elongated flexible member for lowering and raising the guide supports to which said bumper is attached, an elongated flexible member for lowering and raising said table guide supports to which said table is attached, and mechanism interconnecting said elongated flexible members for balancing the weight of the bumper against the weight of the table.

3. An automatic bowling pin setting and resetting machine having a vertically movable table for setting and resetting bowling pins on a bowling alley, a bumper for stopping a thrown bowling ball hanging across the pit of the bowling alley, a vertically movable support to which said bumper is attached, elongated flexible members connected to said vertically movable table and

said vertically movable bumper support, a device for interconnecting said elongated flexible members to cause said table and bumper to counterbalance each other and thereby decrease the amount of force required to move each.

4. In an automatic bowling machine having a vertically movable table for setting and resetting bowling pins on a bowling alley and a vertically movable bumper hanging across the pit of the bowling alley to stop thrown bowling balls, a device interconnecting said table and said bumper to counterbalance one against the other and mechanism for lowering and raising said table each time a bowling ball has been thrown.

5. In an automatic bowling pin setting and resetting machine having a bowling ball bumper, and a spotting and respotting table, mechanism interconnecting said bumper and table comprising movable supports associated with the table, movable supports associated with said bumper, an elongated member for lowering and raising the supports with which said bumper is associated, a member for lowering and raising said table supports, and mechanism interconnecting said members for balancing the weight of the bumper against the weight of the table.

6. In an automatic bowling pin setting and resetting machine having a bumper for stopping bowling balls and a table for engaging, gripping, lifting and replacing standing bowling pins on a bowling alley, a support for said table adapted and arranged to suspend said bumper for vertical movement, and mechanism interconnecting said and arranged to suspend said bumper for vertical movement, and mechanism interconnecting said table and said bumper to enable one to counterbalance the other.

7. In an automatic bowling pin setting machine, a ball stopping member movable up and down with respect to a bowling alley for performing an operation in one portion of the operating cycle of the automatic pin setting machine, a pin positioning member movable up and down with respect to the bowling alley for performing another operation in the machine cycle, and mechanism for counterbalancing the ball stopping member against the pin positioning member to reduce the amount of power required to raise and lower said members.

8. In an automatic bowling pin setting machine a pin handling device movable up and down with respect to a bowling alley to position bowling pins on the bowling alley, an operating member for limiting the amount of travel of bowling balls and bowling pins, and mechanism counterbalancing said device and member against each other to cause said device and member to travel up and down with respect to the bowling alley whenever either of said members is moved a predetermined distance to perform its respective operating function.

9. An automatic bowling pin setting and resetting machine having a vertically movable table for setting and resetting bowling pins on a bowling alley, a vertically movable bumper for stopping a thrown bowling ball hanging across the pit of the bowling alley, elongated flexible members supporting said table and said bumper, a device for interconnecting said elongated flexible members to cause said table and bumper to move predetermined distances of travel in opposite directions each time one of said members is moved a predetermined distance for balancing the weight of the table against the weight of the bumper.

10. In an automatic bowling pin setting and resetting machine, a table for setting and resetting standing bowling pins on a bowling alley, a bumper hanging across the pit of the bowling alley for stopping thrown bowling balls, a set of elongated flexible members connected to and supporting said table at one end and connected to a set of pulleys of a predetermined diameter at the other end, a second set of elongated flexible members connected at one end to and supporting said bumper and connected to a second set of pulleys having a different diameter than that of the first mentioned set of pulleys at the other end, and mechanism for interconnecting said pulleys for rotation to raise and lower said table and bumper in substantially opposite directions a predetermined distance each time a bowling ball is thrown for balancing the weight of the bumper against the weight of the table.

11. In an automatic bowling pin setting machine, a movable bumper for stopping thrown bowling balls, a table traveling towards and away from a bowling alley for engaging, gripping, lifting and replacing standing bowling pins on the bowling alley, mechanism interconnecting said table and said bumper to counterbalance the table with the bumper, and mechanism for lowering and raising said table, while it is counterbalanced by said bumper a predetermined distance each time a bowling ball is thrown to engage, grip, lift, 30 and replace bowling pins on the bowling alley after the first ball is thrown.

12. In an automatic bowling pin setting machine, a member for positioning bowling pins on a bowling alley, said member being adapted and arranged to travel up and down with respect to the bowling alley, a ball bumper for stopping thrown bowling balls, said bumper being mounted for up and down movement with respect to the bowling alley, mechanism for lowering and raising said member a predetermined distance in each cycle of the pin setting machine, a second 35

5 mechanism for raising and lowering said ball bumper a predetermined distance in each cycle of a pin setting machine, and a device for interconnecting said mechanisms to counterbalance said member and said bumper with each other so that they will move in substantially opposite directions whenever either is actuated.

13. In an automatic bowling pin setting machine, a pin positioning member and a ball stopping member adapted to be raised and lowered in each operating cycle of the bowling pin setting machine to move said members into and out of operating position, and mechanism interconnecting said pin positioning member and ball stopping member to balance one against the other to thereby reduce the amount of power required to raise and lower either of said members.

14. In an automatic bowling pin setting machine, a pin handling device movable up and down with respect to a bowling alley, a ball stopping device for stopping thrown bowling balls, said device being movable up and down with respect to the bowling alley, mechanism for raising and lowering said devices in opposite directions 25 a predetermined distance in each operative cycle of the automatic bowling pin setting machine, and counterbalancing means interconnecting said devices to balance one device against the other.
